(57) **CLAIM**

The ornamental design for the network bridge, as shown and described.

DESCRIPTION

FIG. 1 is a front, right and top perspective view of the network bridge with a US-style plug element shown as environment in broken lines;

FIG. 2 shows a rear, left, and bottom perspective view of the network bridge with a US-style plug element shown as environment in broken lines;

FIG. 3 shows a front elevation view of the network bridge; FIG. 4 shows a rear elevation view of network bridge with a US-style plug element shown as environment in broken lines;

FIG. 5 shows a right side elevation view of the network bridge, the left side elevation view being a mirror image thereof; and,

FIG. 6 shows a top plan view of the network bridge, the bottom plan view being a mirror image thereof.

The broken lines on the front surface shown in FIGS. 1 & 3 illustrate portions of the network bridge that form no part of the claimed design. Further, the broken lines illustrating the plug element in FIGS. 1, 2, & 4 form no part of the claimed design.
